ATTORNEY

UNITED STATES PATENT OFFICE.

WILLIAM A. TEBO, OF ANTHONY, RHODE ISLAND, ASSIGNOR TO DRAPER CORPORATION, OF HOPEDALE, MASSACHUSETTS, A CORPORATION OF MAINE.

AUTOMATICALLY THREADING LOOM SHUTTLE.

Application filed August 11, 1928. Serial No. 299,021.

This invention relates to automatically threading loom shuttles of that general class which cooperate with a filling detector or feeler at the replenishing side of the loom.

5 It has been found in practice that when the shuttle has been boxed at the filling replenishing side of the loom and the feeler is to enter the feeler opening to ascertain the condition of the filling on a detecting beat, the thread 10 or filling extending from the cloth selvage to the side delivery eye of the shuttle, which is then adjacent the outer end of the shuttle box, will frequently take position in front of the feeler opening and be broken by the feeler. 15 In attempts to overcome this objection, it has been proposed to equip the loom with mechanism to depress the filling-beyond the zone of action of the feeler on detecting beats, but such depressing mechanism complicates the 20 loom construction and adds operating devices at a part of the loom where they may interfere with the work of the loom attendant.

One of the objects of the present invention is to provide an automatically threading loom 25 shuttle with simple and effective means whereby the thread or filling extending between the cloth selvage and shuttle at the replenishing side of the loom may be positioned so that the feeler at this side of the loom may 30 enter the feeler slot and detect the condition of the filling without liability of breaking the length of filling extending to the cloth selvage.

In accordance with the present invention, 35 the shuttle is provided with a feeler slot in the front wall thereof through which the feeler at the replenishing side of the loom passes on a detecting beat to feel for the filling, and at one side of the feeler slot the front 40 wall of the shuttle is provided with a thread groove preferably below the feeler slot, and in order that the thread as it is delivered from the side delivery eye may be unerringly directed into the longitudinally extending 45 thread groove at the side of the feeler slot, the invention provides a thread guide at the exit of the side delivery eye for directing the thread downwardly into the longitudinal thread groove, with the result that on a detecting beat the feeler may enter the feeler slot without obstruction from the length of the thread extending between the cloth selvage and the shuttle eye.

The invention and novel features thereof 55 will best be made clear from the following

description and the accompanying drawings of one good form thereof.

In the drawings:

Fig. 1 is a perspective view of portions of a filling replenishing loom having the feeler mechanism at the replenishing side and showing the shuttle of the present invention associated therewith, some of the parts being broken away;

Fig. 2 is a side perspective view of a shuttle 65 containing the present invention;

Fig. 3 is an enlarged side elevation of the delivery or eye portion of the shuttle showing the thread or filling directed into the longitudinally extending thread groove; and

Fig. 4 is a cross-section of the shuttle 70 through the feeler slot.

The feeler mechanism and feeler which are located at the replenishing side of the loom may be of any usual or well-known construction, but for the purposes of explanation of the invention, the feeler mechanism herein illustrated is of the character more fully shown and described in the patent to Edward A. Cunniff, No. 1,649,776, dated November 15, 80 1927.

The magazine or hopper containing the filling carriers which are to be transferred to the shuttle is partly shown at 1, Fig. 1, and associated therewith is the transferer 2 mounted on the usual stud or shaft 3 and having a downwardly extending arm 4 to which is pivotally connected at 5 the usual replenishing dog 6 adapted to be struck by a bunter on the lay on call for replenishment of filling.

As hereinbefore noted, the feeler mechanism may be of any of the usual types now employed at the filling replenishing side of the loom and as shown in the present instance it comprises a feeler stand 7 suitably mounted on a bracket 8 and having the feeler 9 extending rearwardly therefrom to enter the usual feeler slot in the front wall of the shuttle on detecting beats to feel for the filling. Associated with the feeler 9 is a transmitter 10 connected to a rocking lever 11 having a projecting portion 12 to cooperate with the actuator 13 to effect replenishment of filling by the transferer when the feeler detects substantial exhaustion thereof, all as more fully shown and described in the Cunniff patent hereinbefore mentioned.

The shuttle 14 is provided with the usual bobbin chamber 15 and has its front wall 16 provided with the feeler slot 17 preferably 110

formed centrally of the front side wall 16 of the shuttle.

Below the feeler slot 17 in the present instance of the invention, the front wall 16 of the shuttle is provided with a longitudinally extending thread groove 18 which, as indicated in Figs. 2 and 4, provides a recess below the feeler slot for the length of filling extending between the cloth selvage and the shuttle, when the latter is boxed at the replenishing side of the loom.

The shuttle 14 is provided with an automatically threading block 19 and the side delivery eye 20 of the shuttle is below the horizontal plane passed through the longitudinal axis of the shuttle, as indicated by the line *a—b*, Fig. 3.

In accordance with the present invention, the thread or filling *c* as it is delivered from the side delivery eye is to be directed into the longitudinally extending thread groove below the feeler slot, and to this end the shuttle is provided with a thread guide at the exit portion of the side delivery eye for directing the thread downwardly into the longitudinally extending thread passage. The thread guiding means may be variously contrived but as indicated in the present instance of the invention it consists of a pin 21 inclined with respect to the longitudinal axis of the shuttle and extending from the top portion 22 of the side delivery eye in an inclined direction, with its lower thread end guiding portion 23 substantially in the longitudinal axis of the thread groove, the result being that as the thread or filling *c* is delivered from the side delivery eye 20 it will be guided downwardly by the thread guiding device or inclined pin 21 into the longitudinally extending thread groove. Normally, the thread or filling *c* will take the position at the lower thread guiding end portion of the inclined pin 21 at the exit end of the side delivery eye, and during the weaving operation the thread may draw more or less over other portions of the guide or pin 21 and consequently not unduly wear the guide or pin, and when the shuttle comes to rest in the filling replenishing box the tension on the thread and its natural tendency to drop will cause it to pass around the lower thread guiding portion of the inclined guide or pin substantially on the longitudinal axis of the longitudinal thread groove.

In some cases it may be desirable to have an additional guide pin or post 24 at the opposite side of the exit portion of the side delivery eye, but the characteristics of the invention are such that when the shuttle comes to rest in the filling replenishing box,

the thread will be directed by the downwardly inclined guide or pin 21 to insure that it enters the longitudinally extending thread guide, with the result that the thread or filling *c* will be held in the thread guide at one side of or below the feeler slot and consequently not obstruct the free entrance of the feeler through the feeler slot on detecting beats.

From the simple expedient of providing a longitudinally extending thread guide below the feeler slot in the front wall of the shuttle and directing the thread or filling unerringly into the longitudinal thread guide by the inclined pin at the entrance of the side delivery eye, all liability of breaking the filling or thread *c* between the cloth selvage and side delivery eye of the shuttle on a detecting beat will be obviated.

As before stated, the side delivery eye if below the horizontal plane passes through the longitudinal axis of the shuttle and intersects the longitudinally extending thread guide 18, while the inclined pin or thread guide insures that the thread will be directed from the exit of the side delivery eye downwardly into and substantially at the center of the longitudinally extending thread guide.

What is claimed is:

1. An automatically threading loom shuttle having a feeler slot and a longitudinally extending thread groove below the feeler slot, a side delivery eye having its exit opening below the horizontal plane passing through the longitudinal axis of the shuttle, and a thread guide at the exit of the side delivery eye inclined downwardly from the top of the eye in a direction to deflect the thread from the exit of the side delivery eye into the thread groove that the thread may be positioned below the feeler slot and permit unobstructed entrance of the feeler at the replenishing side of the loom.

2. An automatically threading loom shuttle having a feeler slot and a longitudinally extending thread groove below the feeler slot, a side delivery eye having its exit opening below the horizontal plane passing through the longitudinal exit of the shuttle, and a thread guide at the exit of the side delivery eye inclined downwardly from the top of the eye with its lower thread engaging portion substantially in the longitudinal axis of the thread groove that the thread may be directed into the thread groove below the feeler slot and permit unobstructed entrance of the feeler at the replenishing side of the loom.

In testimony whereof, I have signed my name to this specification.

WILLIAM A. TEBO.
